Charles T. LaMont
By Wm. H. C. G.
C. W. W.

UNITED STATES PATENT OFFICE.

CHARLES T. LA MONT, OF MILWAUKEE, WISCONSIN.

STOCKING MARKER.

Application filed May 16, 1927. Serial No. 191,804.

This invention relates to stocking markers. In the manufacture of full-fashioned stockings, it is the regular practice to knit the stockings on different machines, as the 5 leg portions and heel tabs are formed on a legger. The fabric or blank must then be taken off the legger and the stitches transferred to the needles of a footer. In order to facilitate the transferring operation of 10 placing each stitch upon the needle bar of the footer, it is customary to spread the rows of stitches.

In my prior application, Serial No. 175,397, filed March 14, 1927, for stocking 15 markers, I have disclosed a hand operated marker which avoids any danger of tearing or marring the fabric of the stocking during the marking operations, as the tool is provided with a yielding conical and rounded 20 point.

This invention is an improvement over that disclosed in my above noted application and objects of such invention are to provide a novel form of marker which has 25 the advantages enumerated in the above identified application of avoiding any danger of tearing the stockings and of facilitating the marking operation, and which also is so constructed that it relieves the 30 operator of a considerable amount of effort as the marker is mechanically drawn forward by any suitable means, preferably by 35 means of a spring so that all that is necessary is that the operator shall guide the marker during its forward stroke.

Further objects are to provide a device in which a holder is provided for the marking instrumentality so that the holder maintains the marker in its correct position, so 40 that it may be readily grasped by the operator, and which is so constructed that easily detachable locking means are provided for normally restraining the marker against forward motion, such means being readily 45 unlocked by slightly lifting the marker at the initiation of the marking operation and being also readily locked by withdrawing the marker to its extreme rearward position after the marking operation has been performed.

An embodiment of the invention is shown in the accompanying drawings in which:

Figure 1 is a side elevation with parts

in section of the device showing it in locked position;

Figure 2 is a view showing the manner in which the marker is unlocked;

Figure 3 is a sectional view on the line 3-3 of Figure 1.

Referring to the drawings, it will be seen that a suitable support, such as a table top 1, has been illustrated, as provided with a standard composed of a pair of upright members 2 provided with projecting feet 3 attached by means of screws 4 to the table 60 or other support. This standard has its two members joined by a transverse upper portion 5, as shown most clearly in Figure 3. It is provided with a fixedly held pin or bolt 6 which is slotted and receives the in-turned end 7 of a coiled spring 8. Preferably, a nut 9 is screwed upon the projecting end of the bolt, as shown in Figures 1 and 3, to lock the bolt in position. Obviously, the tension of the spring may be controlled by the rotation of the bolt, such bolt being subsequently locked in place. Also, it is to be noted that, if desired, suitable means may be provided for restraining the bolt against rotation, in addition to the 70 clamping action of the nut, although it is preferable to have the bolt so that it may be rotated to secure the correct adjustment for the spring.

A transversely extending pin or bolt 10 projects adjacent the upper portion of the standard and guides a slotted bar 11. This slotted bar 11 is elongated and carries at its outer end the marker 12. The marker is preferably provided with a handle 13 at 85 right angles to its body portion, and as described in my above noted application, is provided with a recess 14 within which the inner end of a plunger 15 is slidably mounted. The plunger is yieldingly pressed outwardly by means of the spring 16 and is preferably provided with a reduced portion 17 within which a limiting screw 18 projects, such screw limiting the motion of the yielding point 15. The yielding point or 90 plunger is provided with an approximately conical end 19 which is rounded so as to give a definitely formed point, although free from any sharp corners or projections which might catch in the stitches of the stocking blank. The elongated bar 11 is provided

with a ring 20 adjacent its outer end. The outer end of the outwardly projecting portion 8' of the spring is passed through the eyelet or ring and suitably secured, so that the spring urges the connecting member or slide inwardly.

A rectangular locking frame 21 is pivotally mounted upon the bolt 10 and is positioned on the outer side of the standard 2.

- 10 It is provided with a relatively wide rear end 22 against which the end of the slide or bar 11 is adapted to contact when the parts are in locked position, as shown in Figure 1.
- 15 It is to be noted also from reference to Figures 1 and 2, that the pin or bolt 6 is provided with a locking lever or latch 23 which is equipped with a forwardly projecting arm 24. A spring 25 extends between the arm 24 of the latch and the rocking frame or cradle 21. The latch 23 is provided with a lip 26 adapted to overhang the transverse part 22 of the rocking cradle or member 21, as shown in Figure 2, under certain conditions. It is also provided with
- 20 an upstanding lip 27 against which a pin 28 carried by the inner end of the bar 11 is adapted to strike when the marker is drawn outwardly to its greatest extent.
- 25

In using the apparatus, assuming that the parts are in locked position, as shown in Figure 1, all that is necessary is for the operator to grasp the handle 13 and rock the marker upwardly. This causes the cradle or restraining member 21 to rock into the position shown in Figure 2, and to be retained in such position by the latch. There-

after the operator rocks the marker downwardly, thus permitting the inner end of the bar 11 to slide clear of the member 22. The

40 spring 8 through its extended portion 8' draws the bar 11 and, consequently, the marker, inwardly towards the standard, the operator merely guiding the marker across the stocking or fabric. The operator is thus

45 relieved of the effort of moving the marker forwardly which, in the course of a day's work, is found to be a considerable strain. After the marking operation has been completed the operator merely draws the

50 marker to its outermost position. This causes the pin 28 to engage the lip 27 and thus rock the latch rearwardly. The spring 25 then rocks the restraining member or cradle 21 into the position shown in Figure

55 1, thus positioning the member 22 at the end of the bar 11 and retaining the bar against inward motion. The operator is then free to release his grip upon the marker and rest it upon the table top, as shown in Figure 1,

60 thus leaving both hands free to remove the work and to position any work in its place.

The yielding point of the marker cooperates directly with this mechanically movable mechanism, for it is obvious that with a rigid point and a mechanically movable

marker, that great danger would be incurred of tearing the fabric of the stocking by the hanging of the point in the stitches as there would then be no yield to the marking point.

However, with the yielding marking point, such point may freely move and ride over the successive stitches even when the device is quickly drawn inwardly by the mechanical means described above.

It will be seen, therefore, that a novel form of stocking marker has been provided by this invention in which the effort of the operator is materially reduced. It is to be noted also that the operator is free to rock the bar 11 laterally, as considerable space is left between the members 2 of the standard. In this connection, attention is directed to Figure 3, from which it will be seen that a coiled spring 29 is positioned within the standard and around the pin or bolt 10. This spring bears against the bar 11 and urges it towards one side of the standard. Preferably, a washer 30 is interposed between the standard and the bar 11 and a similar washer 31 is positioned between the spring and the bar. This permits the utmost freedom in manipulating the bar, so that in case the work is not laid straight upon the support, the marker may correspondingly be moved in a slanting direction.

Although the invention has been described in considerable detail, such description is intended as illustrative rather than limiting as the invention may be variously embodied and as the scope of such invention is to be determined as claimed.

I claim:

1. A marker for full-fashioned stockings comprising a support, a standard extending upwardly therefrom, a member slidably guided by said standard, and a stocking marking instrumentality carried by said member and adapted to be drawn across the stocking to spread the stitches.

2. A marker for full-fashioned stockings comprising a brace, a standard carried thereby, a slidably mounted bar carried by said standard, yielding means drawing said bar in one direction with reference to said standard, and a stocking marking instrumentality carried by said bar and adapted to be drawn across the stocking to spread the stitches.

3. A marker for full-fashioned stockings comprising a brace, a standard carried thereby, a slidably mounted bar carried by said standard, resilient means drawing said bar in one direction with reference to said standard, and a stocking marking instrumentality carried by said bar, said stocking marking instrumentality having a yielding contact point adapted to be drawn across the stocking to spread the stitches.

4. A marker for full-fashioned stockings

comprising a manually manipulable member provided with a yielding marking point adapted to be drawn across the stocking to spread the stitches, a bar pivotally connected to said member, and yielding means for drawing said bar in one direction.

5. A marker for full-fashioned stockings comprising a slidably mounted bar, mechanical means urging said bar in one direction, 10 and a marking member carried by said bar and having a yieldingly mounted marking plunger adapted to be drawn across the stocking to spread the stitches.

6. A marker for full-fashioned stockings 15 comprising a slidably mounted bar, mechanical means urging said bar in one direction, and a marking member carried by said bar and having a yieldingly mounted marking plunger adapted to be drawn across the 20 stocking to spread the stitches, and latching means for temporarily restraining the bar against sliding motion.

7. A marker for full-fashioned stockings comprising a standard, a bar slidably carried by said standard and having an outer 25 end, a stocking marker carried by said outer end and provided with a slidably mounted spring pressed plunger adapted to be drawn across the stocking to spread the stitches, a 30 spring urging said bar in one direction with

reference to said standard, a rocking locking member for temporarily restraining said bar against motion, and a latch for engaging said locking member and holding said locking member in inoperative position.

8. A marker for full-fashioned stockings comprising a standard, a slotted bar slidably carried by said standard, a spring carried by said standard and urging said bar in one direction, a rocking locking cradle pivotally 40 mounted upon said standard and having a portion adapted to rock into the path of movement of said bar, said cradle being rocked by a rocking motion imparted to said bar, a latch pivotally mounted upon said 45 standard and having a lip adapted to engage said cradle and hold said cradle in inoperative position, a finger carried by said latch, a projecting member carried by said bar and adapted to engage said finger to disengage 50 said latch from said cradle and a member carried by said bar and having a point adapted to be drawn across the stocking to spread the stitches.

In testimony that I claim the foregoing I 55 have hereunto set my hand at Milwaukee, in the county of Milwaukee and State of Wisconsin.

CHARLES T. LA MONT.
